UNITED STATES PATENT OFFICE.

FRANK R. McGEE, OF STEUBENVILLE, OHIO.

CHECKERWORK FOR REGENERATIVE CHAMBERS.

Application filed August 6, 1926. Serial No. 127,650.

This invention relates to regenerative chambers and more particularly to checkerwork for such chambers, and has for one of its objects the provision of a novel form of 5 checkerwork in which an even distribution of gas is had over the entire checkerwork thereby providing efficient operation.

Another object is to provide a novel form of checkerwork from which the dust may be 10 readily removed while the chambers are in operation.

Another object is to provide a checkerwork which will, due to its comparatively simple construction, have a lower installation and 15 maintenance cost.

Another object is to provide a checkerwork having the novel design, construction and combination of parts hereinafter described and illustrated in the accompanying drawings. 20

In the drawings:

Figure 1 is a plan of a checkerwork adapted for use in a hot blast stove or the like, constructed in accordance with this invention.

25 Figures 2 and 3 are sectional elevations taken on the lines II—II and III—III, respectively, of Figure 1.

Figure 4 is a plan of a slightly modified form of checkerwork also adapted for use 30 in a hot blast stove and constructed in accordance with this invention.

Figure 5 is a sectional elevation on the line V—V of Figure 4.

Figure 6 is a plan of a still further modified form of checkerwork particularly adapted 35 for use in regenerative chambers of open hearth furnaces.

Figures 7 and 8 are sectional elevations 40 on the lines VII—VII and VIII—VIII of Figure 6.

Referring more particularly to Figures 1 to 3 of the drawings, the numeral 2 designates the shell of a hot blast stove or other regenerative chamber enclosing a checker- 45 work A.

The checkerwork A is composed of a plurality of vertically disposed horizontally spaced, parallel walls 3 composed of a series of bricks or tiles 5 laid up edgewise one on 50 top of the other. The spaces between the walls 3 form gas channels 4 through which the heated gases and the gases to be heated pass.

Each of the tiles or bricks 5 have their 55 corner edges cut away or shaped as at 6 to

form one fourth of a circular recess or opening 7 formed by the abutting corners of four adjoining bricks. The recesses 7 are adapted to receive the reduced ends of combined spacing and baffle bricks or tiles 8, which are 60 built into and extend from one wall 3 to the next wall transversely of the gas channels 4.

The bricks 5 are each provided with a centrally arranged circular opening 9, which openings in each of the several walls are preferably in alignment so as to form transverse gas passageways between the several gas channels 4, thus permitting a transverse flow 65 of the gases to equalize the flow and pressure of the gases in each of the gas channels. 70

Checkerwork constructed as above described prevents the forming of dead or cool areas due to the transverse gas flow between the gas channels, and also is more efficient than checkerwork as heretofore generally 75 constructed since there is less surfaces upon which dust may collect.

The checkerwork shown in Figures 4 and 5, which is designated generally by the letter B, and is adapted for use in a hot blast stove 80 or the like, is composed of a plurality of vertical walls 10 and 12 arranged at right angles to each other and intersecting to form rectangular or square gas channels 13.

The walls 10 and 12 are each composed of 85 a series of bricks or tiles 14 laid edgewise, one on top of the other. The bricks or tiles 14 have their end faces beveled from each side at approximately ninety degrees, as at 15, so that the ends of four bricks may be 90 interlocked in forming the intersecting walls 10 and 12, and the top and bottom faces of the bricks or tiles are notched, as at 16, so that the notches of abutting bricks will form rectangular openings 16^a. 95

The walls 10 and 12 are spaced apart a distance equal to the width of the side face of one of the bricks or tiles 14, so the bricks or tiles of each wall are interlocked between the end faces of two abutting tiles of the two 100 walls extending at right angles.

The walls 10 have combined spacing and baffling tiles or bricks 17 built into the alternate horizontal rows of openings 16^a and extending transversely of the gas channels 13, 105 while the walls 12 have combined spacing and baffling tiles 18 built into the alternate horizontal rows of openings 16^a alternating with the rows of openings in which the tiles or bricks 17 are built, so that the tiles or bricks 110

17 and 18 extend at right angles to each other, one above the other. The open or vacant openings 16^a form gas passageways between the gas channels 13 to permit a transverse flow of the gases to equalize the flow and pressure of the gases in each of the gas channels.

The arrangement of the combined spacing and baffling bricks 17 serves to cause the gases 10 to assume a staggered or twisting flow path through the gas channels 13, thereby causing a greater heat exchange than would be possible in a straight flow path.

The checkerwork of Figures 6 to 8, designated generally by the letter C, is particularly adapted for use in the regenerative chambers of open hearth furnaces and the like, where a horizontal flow of the gases is desired. The checkerwork C comprises a 20 dust chamber base composed of transverse, vertically disposed, spaced walls 20. The spaces 21 between the walls 20 form dust pockets into which the dust from the checkerwork is collected.

25 A plurality of vertically disposed, longitudinal checker walls 22 are supported on the walls 20 and spaced transversely from each other to form gas channels 22^a. The walls 22 are composed of a series of bricks or tiles 23 laid up edgewise, one on top of the other. The bricks or tiles 23 have two opposite corners cut away on an angle, as at 24, and the other two opposite corners cut away on a curve forming a segment of a circle, as at 25, 30 and the side edge of the brick intermediate the curved cut corners 25 is provided with a rectangular recess 26. The bricks or tiles 23 are laid up so that the angle cut corners 24 of four bricks abut to form square openings 27, while the curved cut corners 25 abut to form circular openings 28, and the recesses 26 of two bricks abut to form a square opening 29. A plurality of combined spacing and baffle bricks or tiles extend transversely of 40 the gas channels 22^a and have their reduced ends inserted and built into the square openings 27. The round or circular openings 28 form communicating gas passageways between the gas channels 22^a, so that the pressure and flow may be equalized in all the gas 45 channels.

The round or circular openings 28 also are used as ports through which suitable cleaning tools or fluid pressure nozzles may be 50 passed when cleaning the dust from the checker walls.

The checkerwork of this invention has many advantages over the checkerwork as ordinarily constructed; it is easier to construct, more durable; there are less surfaces to catch and retain dust; the gases may flow more readily therethrough; and the formation of cool or dead areas is entirely eliminated due to the provision of transverse flow 60 passageways which permit the equalization

of gas pressure and flow in the several gas channels.

While I have shown and described certain specific embodiments of my invention, it will be understood that I do not wish to be limited thereto since various modifications have been and may be developed without departing from the scope of my invention as defined in the appended claims.

I claim:

1. A checkerwork for regenerative chambers comprising a plurality of vertically disposed spaced partition walls forming gas channels, said walls being composed of a plurality of individual tiles laid edgewise one on the other, said tiles being recessed to provide transverse openings in said walls, some of said openings remaining unobstructed to form gas passageways between said gas channels, and solid tiles extending transversely of 80 said gas channels and having their ends built into others of said openings and serving to maintain said walls in spaced relation and to baffle the gases passing through said channels.

75

2. A checkerwork for regenerative chambers comprising a plurality of vertically disposed spaced partition walls forming gas channels, said walls being composed of a plurality of individual tiles laid edgewise one on the other, said tiles being recessed to provide transverse openings in said walls, some of said openings remaining unobstructed to form 90 gas passageways between said gas channels, and solid tiles extending transversely of said gas channels for maintaining said walls in spaced relation and baffling the gases passing through said channels, said last named tiles comprising a body portion and reduced end portions forming shoulders at each end of 95 said body portion, said last named tiles having their reduced end portions built into others of said openings and their shoulders abutting said walls.

90

3. A checkerwork for regenerative chambers comprising a plurality of vertically disposed spaced partition walls forming gas channels, said walls being composed of a plurality of individual tiles laid edgewise one on the other, said tiles being recessed at their 110 centers to provide transverse openings therethrough and having their corner portions recessed so that the corners of abutting tiles will form other openings, and solid tiles extending transversely of said gas channels for maintaining said walls in spaced relation and for baffling the gases passing through said channels, said last named tiles comprising a body portion and reduced end portions forming shoulders at each end of said body portion, and said end portions being built into said 115 last named openings so that said shoulders abut said walls.

105

4. A checkerwork for regenerative chambers comprising a plurality of vertically dis-

120

125

130

posed spaced partition walls forming gas channels, said walls being composed of a plurality of individual tiles laid edgewise one on the other, said tiles being provided with 5 circular recesses at their centers forming transverse circular openings through said walls, said tiles also having their corner portions recessed in the form of a segment of a circle so that the corners of abutting tiles will 10 form other circular openings, and solid tiles extending transversely of said gas channels for maintaining said walls in spaced relation and for baffling the gases passing through said channels, said last named tiles comprising a body portion circular in cross-section 15 and reduced circular end portions forming shoulders at each end of said body portion, said end portions being built into said last named circular openings, and said shoulders being abutted against the side faces of said 20 wall.

In testimony whereof, I have hereunto set my hand.

FRANK R. McGEE.
